WATER HEATER ATTACHMENT

Filed April 25, 1929

Fig. 1,

INVENTOR:
Lewis Glashow
BY Max D. Oldmann

ATTORNEYS.

UNITED STATES PATENT OFFICE

LEWIS GLASHOW, OF NEW YORK, N. Y.

WATER HEATER ATTACHMENT

Application filed April 25, 1929. Serial No. 357,921.

The present invention relates to an improved connecting unit for a hot water supply system.

The primary object of my invention is to provide a device which may readily be fixed to the boiler of a furnace in leak-proof manner without the use of any packing and screw bolts.

A second object is to provide a water distributing unit whereby the cold water flowing into a reservoir will be properly circulated through the boiler.

With these and other objects in view my invention consists in the novel construction, combination and arrangement of elements as will be hereinafter more fully described and shown in the accompanying drawings.

In the drawings in which similar reference characters denote corresponding parts:

Fig. 1 is a diagrammatic showing of my distributing or connecting unit in position of use;

Fig. 2 is a longitudinal section view of my device; and

Fig. 3 is a full section along line 3—3 of Fig. 2.

The heating system is of the usual type and includes the heating furnace having therein a boiler 10, water circulating tubes or heating units 11 mounted in the boiler and a reservoir tank 12 outside said furnace in which hot water is stored for use after passing through said circulating tubes in said boiler.

In order to afford an easy means of connection of the circulating tubes 11 to the incoming cold water supply pipe 13 and also to the outflowing pipe 14 to the hot water reservoir, I provide my new distributing head or unit 15 which may be a hollow casting of brass, bronze or other suitable metal. The said unit is provided with an integrally formed partition 16 which divides the hollow interior into two entirely separate compartments A and B respectively. The front wall 15' of my unit is provided with two threaded openings 17 and 18 respectively, each communicating with one of said compartments. Similar threaded openings 19 and 20 are provided at the top and bottom

faces 15² and 15³ respectively. The rear wall 15⁴ of my device is comparatively thick and may for instance have a thickness of one and a half inches or more and is provided with a plurality of holes 21, an equal number communicating with each of said two inner compartments A and B, said holes being regularly arranged in the said rear wall portion. The rear wall portion 15⁴ of my device is circular in section and is provided with the external thread 22. Suitable threaded plugs 23 are provided and adapted to fit into any one of the holes 17-20 inclusive.

My device is used as follows:

The open ends of boiler water circulating tubes 11 are suitably mounted in the holes 21 as by brazing or welding and then the member 15 is tightly screwed into the wall 10' of the furnace boiler. Since said member 15 is of brass and threaded no packing of any kind is necessary to insure a leak-proof joint. The cold water inlet pipe 13 from the reservoir tank 12 is attached to opening 17 or 19 leading to compartment A and the other one of said two openings is sealed with a plug 23. The hot water outlet pipe 14 which also leads from the water reservoir tank 12 is attached either to opening 18 or 20 and the other one of said two openings is also sealed with a plug 23. The double set of openings to each compartment is for convenience of attachment of said pipes 13 and 14, the respective pipes being attached to the most accessible opening of each of the respective sets of the openings in said two compartments.

The circulation of water is as follows:

Cold water flows through pipe 13 into compartment A and then enters and flows through said tubes 11, where it is heated, and out from said tubes through compartment B, through pipe 14 and into tank 12 whence it is fed to outlet taps in usual manner.

My device thereby affords a simple distributing unit for the water supply and reduces to a minimum the possibility of leaks, and may be modified in various ways without departing from the spirit of my inven-

tion. I therefore, do not wish to be limited to the details shown and described.

What I claim is:—

1. As an article of manufacture for a hot water supply system which includes a reservoir for hot water and heating units on the boiler of a heating furnace, a distributing unit for the inflowing cold water to and the outflowing heated water from said heating units to said reservoir, comprising a hollow copper alloy casting provided externally with a threaded portion adapted to screw into the boiler of said furnace, and form a tight joint without packing by reason of the composition of said casting, a comparatively thick rear wall to said casting, an integrally formed partition in the interior of said casting dividing said interior into two separate compartments, a plurality of uniformly distributed openings in said rear wall leading to each of said compartments for connection thereto of a plurality of heating units, and two sets of threaded openings in the other walls of said casting each set communicating with one of said compartments, one of each set being adapted to be connected with said reservoir when in use and the remaining ones not in use being adapted to be sealed.
2. As an article of manufacture for a hot water supply system having a boiler, a distributing unit for the inflowing cold water and outflowing hot water comprising a hollow brass casting provided externally with a threaded portion adapted to screw into a wall of said boiler and make a tight joint therewith without packing by reason of the composition of said casting, a comparatively thick wall at one portion of said casting, an integrally formed partition in the interior of said casting dividing said interior into two separate compartments, a plurality of uniformly distributed openings in said thick wall leading to each of said compartments for connection thereto of a plurality of heating tubes and two pairs of threaded openings in the other walls of said casting, each pair communicating respectively with one of said compartments, one hole of each pair being in a different wall of said casting than the other hole thereof in order that pipe connection to said compartments in said casting may be made to the most convenient hole of each of said pairs and a threaded plug for closing the unused hole of each of said pairs.

55 Signed at New York, this 23rd day of April, 1929.

LEWIS GLASHOW.
